UNITED STATES PATENT OFFICE

2,668,306

FLOOR POLISHER

Erhard O. Kohl, Massillon, Ohio, assignor to The Hoover Company, North Canton, Ohio, a corporation of Ohio

Application September 13, 1950, Serial No. 184,658

1 Claim. (Cl. 15—50)

1

This application relates to floor polishers and more particularly to an attachment for a floor polisher for the application of liquid wax to the floor during floor polishing operations.

Specifically, according to the present invention, a container for liquid wax is detachably secured to the rear of a floor polisher so that it may be readily attached thereto when it is desired to apply wax to the floor. The container is divided into two chambers by a horizontal partition. The upper chamber is adapted to contain liquid wax and the partition is provided with a valved opening leading to a bottom distributing chamber. The bottom of the lower distributing chamber is closed by a fine mesh screen which serves to support a porous wax spreading cloth and to distribute the wax over the cloth. An operator for the valve extends upwardly through the upper chamber and is positioned to be contacted by the propelling handle of the polisher so that downward movement of the handle will open the valve when it is desired to apply wax to the floor.

Other objects and advantages of this invention will become apparent as the description proceeds when taken in connection with the accompanying drawings in which:

Figure 1 is a side elevation of a floor polisher with the waxing attachment of this invention applied thereto;

Figure 2 is a cross-sectional view of the waxer attachment taken on line 2—2 of Fig. 1, looking in the direction of the arrows; and

Figure 3 is a plan view of the polisher and attachment of Fig. 1.

Referring to the drawings the reference numeral 10 represents the main frame as a floor polisher of known construction having a plurality of rotatable brushes 11 driven by a motor housed within the hood 12. The polisher is adapted to be propelled about during polishing operation by handle 13 pivoted to the frame 10 by pivot pintles 14.

A wax container 15 is attached to the pintles 14 by a pair of arms 16, having slots 17 which slide over the pintles 14 inside the bail arms of the handle 13 and pivoted to the container 15 by pintles 18 preferably welded to the side walls of the container 15 as shown in Fig. 2. The container 15 is formed with a top portion 19 and a bottom portion 20 which extends about the periphery of the top portion 19 and has a ledge 21 extending inwardly toward the center of the container 15. The ledge 21 forms a support for a wax distributing screen 22 which supports a porous cloth wax applicator 23 clamped about 55 the bottom portion 20.

2

the periphery of bottom portion 20 by a clamping band 24 held in clamping position by a releasable latch 25.

The interior of the top portion 19 of the container 15 is divided into two chambers by a horizontal partition 26 having a flange 27 preferably brazed or otherwise secured to the inner wall of the portion 19. The partition 26 is provided with a central opening 28 in which a valve seat member 29 is suitably secured. The valve seat 29 cooperates with a valve 30 preferably made of rubber such as "neoprene" which is not affected by oils in the liquid wax. A valve stem 31 has its lower end secured to the valve 30 and extends upwardly through a guide 32 secured in the top of the container 15 by a closure 33 which may be brazed or otherwise secured to the container 15.

The valve 30 is spring-biased upwardly by a spring 34 resting against the partition 26 at its lower end and at its upper end against a downwardly facing disc 35 which abuts a shoulder 36 on the valve stem 31. A pin 37 passes through the upper end of the stem 31 to form a stop to prevent excess opening of the valve 30.

The upper end of the stem 31 is positioned immediately below a roller 38 clamped to the handle 13 by a suitable clamping band 39. The container 15 is provided with a filling opening closed by a cap 40 as shown in Fig. 2.

Operation

When it is desired to apply wax to the surface being polished the closure 40 is removed and the container 15 filled with wax as shown in Fig. 2. The closure 40 is then replaced and the slots 17 in the arms 16 slid over the pintles 14 on the inside of the handle bails of the handle 13. Since the arms 16 are pivoted to the pintles 14 and to the pintles 18 the wax applying cloth 23 will rest horizontally upon the surface being polished immediately to the rear of the polisher.

The polisher is then propelled about over the surface being polished and when it is desired to apply wax the handle 13 is depressed so that the roller 38 will contact the top of the valve stem 31 and open the valve 30 to supply liquid wax to the top of the distributing screen 22 and to the wax applying cloth 23.

From the foregoing, it can be seen that according to this invention a simple attachment is provided for a floor polisher for the application of liquid wax to the surface being polished which requires no modification of the polisher, except the application of the clamping band 39 to the handle 13.

While I have shown but a single embodiment of my invention it is to be understood that that embodiment is to be taken as illustrative only and not in a limiting sense. I do not wish to be limited to the particular structure shown and described but to include all equivalent variations thereof except as limited by the scope of the claim.

I claim:

A combined floor polisher and waxer comprising, a body, polishing brushes rotatably carried by said body, a propelling handle pivoted to said body and extending upwardly and rearwardly therefrom during polishing operations, a wax containing receptacle at the rear of said body, 15 a wax applicator secured to the bottom of said receptacle, a pair of arms pivoted to said receptacle and to said body whereby said receptacle is propelled along behind said body with said applicator resting upon the surface being polished, valve means in said receptacle for dis-

pensing wax to said applicator and an actuator for said valve means positioned to be contacted by said handle upon downward pivotal movement thereof.

ERHARD O. KOHL.
